UNITED STATES PATENT OFFICE.

JOHN A. DUGGAN, OF QUINCY, MASSACHUSETTS.

STORE-SERVICE APPARATUS.

SPECIFICATION forming part of Letters Patent No. 380,315, dated April 3, 1883.

Application filed May 17, 1886. Serial No. 202,381. (No model.)

To all whom it may concern:

Be it known that I, JOHN A. DUGGAN, a citizen of the United States, residing at Quincy, in the county of Norfolk and State of Massachusetts, have invented certain new and useful Improvements in Cash-Carrier Apparatus; and I do hereby declare that the following is a full, clear, and exact description of the invention, which will enable others skilled in the art to which it appertains to make and use the same.

This invention relates to cash-carriers; and it consists in the novel construction and combination of the parts, hereinafter fully described and claimed.

In the drawings, Figure 1 is a side view of the carrier, and Fig. 2 is an end view of the same. Fig. 3 is a side view of the cash-box. Fig. 4 is a side view of the cash-box connected to the carriage, showing the air-buffer in longitudinal section. Fig. 5 is a vertical cross-section through the cash-box, and Fig. 6 is a plan of the same. Fig. 7 is a side view of the buffer and portions of the carrier, drawn to an enlarged scale, and shows also the retaining-catch for preventing the carriage from starting prematurely.

The track *a* is formed of wire or other similar material, and is provided with flexible ends *a'*, which wind about the circumference of the eccentrics *b*, secured upon the spindles *b'* at each end of the track. Pulleys *c* are also secured upon the said spindles, and have cords *c'* passing around them and provided with weights *l* at their free ends, which weights are, for convenience, made in the form of handles. The two eccentrics *b* are oppositely secured upon their spindles, so that when one end of the track is raised the other end will be correspondingly depressed. The spindles *b'* are journaled in the brackets *l'*, secured to a wall or other fixed support.

A carriage, *k*, is provided with wheels *k'*, journaled upon spindles *w*, and runs back and forth upon the track. A cash-box, *d*, is secured to the said carriage by means of the extension-bars *h* and *i*, which permit of the cash-box being drawn up or down, and also allow it to be rotated. A hook, *o*, is provided at the top of the cash-box, which engages with the pin *p*, projecting from the side of the carriage, when

the said cash-box is pushed up and turned around by the handle *d'*. The carriage is provided with an extension, *q*, at each end, which supports a piston, *s*, encircling the track and engaging with an air-buffer, *r*, at the end of the track. The cash-box is preferably made of glass, so that its contents may be seen, and the top of it has also the holes *f* for that purpose. A lid, *e*, slides upon the central pivot, *g*, at the top, and is provided with the knob *f'* for turning it.

The handles or weights *l* are sufficient to hold the track taut for ordinary weights; but when heavy parcels are attached to the carriage the handles are attached to the hooks *g* after being drawn down. The hooks *g* slide vertically in the fixed brackets *m*, and are connected to them by the tension-springs *m'*.

In order to prevent the carriage from starting prematurely, and to accelerate its departure as soon as it is drawn to its highest point, the device shown in Fig. 7 is used. The buffer *r* is connected to the spindle *b'* by the link *u*, which has a boss, *u'*, surrounding the said spindle. A retaining-catch, *v*, is pivoted to the eccentric *b* by the pin *v'*, and engages automatically with the front spindle, *w*, of the carriage, and holds the carriage while it is being raised from its lowest to its highest position by the eccentric. The motion of the eccentric causes the catch *v* to draw back the carriage and force the piston *s* into the buffer, compressing the air within it. When the carriage reaches its highest position, the catch *v* strikes against the boss *u'* of the link, as indicated by the dotted lines in Fig. 7, and releases the carriage, which is immediately started by the compressed air in the buffer.

What I claim is—

1. In a cash-carrier, the combination of the track provided with flexible ends, the two oppositely-arranged eccentrics secured upon revoluble spindles at the ends of the track, the pulleys also secured to the said spindles, and the cords and weights for turning the pulleys and keeping the track taut, substantially as set forth.

2. The combination of the cash-carrier track, the revoluble eccentric having the flexible end of the track secured to it, the pulley secured upon the eccentric spindle, the cord secured

to the pulley and provided with a handle, and the vertically-sliding hook provided with a tension-spring for engaging with the said handle and keeping the track taut, substantially 5 as set forth.

3. The combination of the wheeled cash-carrier carriage having the projecting pin *p*, the cash-box, and the extension-bars *h* and *i*, connecting the said cash-box to the carrier, so that 10 it may be drawn up and down and rotated to engage with the said pin, substantially as set forth.

4. The combination of the cash-carrier track and the revolute eccentric for raising its end, 15 the wheeled carriage running on the track and

provided with the extension *q* and piston *s*, the air-buffer *r*, the link connecting the buffer with the eccentric spindle, and the retaining-catch *v*, pivoted to the eccentric and engaging automatically with the carriage, whereby the 20 said piston is drawn back, compressing the air within the buffer while the carriage is being released and until the catch strikes upon the boss of the said link and releases the carriage, substantially as set forth.

JOHN A. DUGGAN.
